shape desired for the discharge surface of the shell. The actual dimensions of the die 30 are a little oversize so that the prongs 37 at the end of the shell 36 are spaced a few thousandths too far apart and can be bent into exact position as determined by a thickness gauge.

The rack bar is lowered until the die 25 is in contact with the shell 36. The rack bar is then struck on the top with a hammer once or twice to bend the prongs at the end of the shell to the exact contour of the die. The die 25 at the bottom of the rack bar 13 is shaped so that it has a "drawing" action over the die 30 rather than a true "forming" action as understood in the die art. The operation is referred to herein as the "forming of the shell," however, using the term in its broader sense.

The die 30 is held in position by a die lock pin 38 clamped against the stem 31 by a set-screw 39 threading through the forward wall of the base.

After the forming of the shell 36 in the manner described above, the shell 36 is screwed onto the rest of the plug 41, as shown in Fig. 4, and the assembled spark-plug is inserted through a bushing 43 and threaded into a face plate 44 of a carriage 45 until the shoulder 47 of the plug comes against the end of the bushing 43.

The carriage 45 rests on the supporting surface 27 and has a width substantially equal to the distance between the guide surfaces 28, best shown in Fig. 2. When the carriage has been moved into position to locate the electrode end of the plug in the proper relation to the path of movement of the rack bar 13, a set-screw 50, threaded into the front of the frame 10, is tightened against the carriage 45 to lock it in position.

The carriage 45 includes a body portion 52, a part of which extends upward at a substantial acute angle to the vertical as shown in Fig. 4. The face plate 44 has a sleeve 53 extending from its back face. This sleeve 53 fits into the up-standing part of the carriage body 52, and is held in the carriage body by a set-screw 54, that extends into a circumferential groove 55 in the sleeve 53 and leaves the sleeve and the face plate 44 free to rotate.

The bushing 43 surrounds the tops of the outside threads of the shell 36 and limits the extent to which the spark-plug can be screwed into the face plate 44 by providing an abutment against which the shoulder of the spark-plug strikes. The bushing 43 has a circumferential groove registering with a groove on the inside surface of the sleeve 53, and a spring 59 confined in these grooves holds the bushing against displacement from the sleeve. The spring 59 yields, however, to permit the bushing to be forced from the sleeve when a longer bushing is to be inserted for a different model of spark-plug.

An electrode adjusting foot 61 has an enlarged

upper end that fits snugly into the socket 23 in the bottom of the rack bar 13. The adjusting foot 61 is held fast in the socket by a set-screw 62 (Figs. 1 and 2), and the rack and pinion mechanism is operated to bring the adjusting foot down against the uppermost prong 37 of the spark-plug shell 36. A thickness gauge 64 is inserted between the center electrode of the spark-plug and the uppermost prong 37 of the shell; the hand-wheel is then operated, and the prong is pressed against the thickness gauge with sufficient force to reduce the clearance between the electrode surfaces to the dimension of the thickness gauge.

The face plate 44 is turned to bring each of the four prongs on the end of the shell 36 successively into position under the adjusting foot 61. Fig. 3 illustrates the manner in which an operator holds the thickness gauge 64 in one hand and turns the hand-wheel 19 with the other hand. The hand-wheel is of such a size in relation to the size of the pinion and other parts that no injury to the plug will be caused with any reasonable force that is applied to the hand-wheel.

The preferred embodiment of the invention has been illustrated and described, but modifications can be made and some features of the invention may be used without others.

I claim:

1. A spark-plug adjusting tool including a member movable up and down in a frame, means supporting a spark-plug with its electrode end under said member and disposed obliquely to the direction of movement of said member, the supporting means including a body through which the spark-plug is inserted, a plate into which the spark-plug screws, and a removable bushing in position to be clamped between a shoulder of the plug and said plate to limit the extent to which the plug can screw into the plate and thereby control the position of the electrodes with respect to the plate and said member.

2. A tool for adjusting the spacing of the electrodes of a spark-plug that has a center electrode surrounded by a plurality of prong electrodes extending from the spark-plug shell, said tool comprising a frame in which is a guideway, a rack bar slidable in the frame toward and from the guideway, a carriage that is movable lengthwise in the guideway and is supported by and held against transverse movement by bearing surfaces of said guideway, means on the frame operable to hold the carriage against movement lengthwise of the guideway, a holder on the carriage with an opening for receiving a spark-plug and an abutment for positioning the spark-plug in a definite position in said holder with the axis of the spark-plug extending at an acute angle to the direction of movement of the rack bar, and a bearing on the carriage in which the spark-plug holder is rotatable about an axis substantially coincident with the axis of the plug.
